UNITED STATES PATENT OFFICE

LEE J. VOORHEES, OF LONG ISLAND CITY, NEW YORK, ASSIGNOR TO NATIONAL CARBON COMPANY, INC., A CORPORATION OF NEW YORK

FLASH LIGHT

Application filed September 15, 1928. Serial No. 306,196.

This invention pertains to improvements in battery operated hand lamps or flashlights, and more specifically to means for securing a more accurate focus in such lamps.

5 Broadly the object of this invention is to provide a hand lamp containing improvements in the structure shown in the applicant's Patent No. 1,668,881, together with improvements in the lateral focusing mechanism shown by H. W. Jones in his Patent Number 1,610,289.

In the hand lamp construction shown in the applicant's above mentioned patent, the irregular shaped central terminal of the 15 lamp bulb seats against the hollow rivet in the bottom of the lamp socket. This tends to throw the lamp bulb out of alignment with the socket so the lamp filament is out of axial alignment with reflector and the projected beam of light is distorted and lessened in intensity. Therefore, one of the specific 20 objects of this invention is to provide a hand lamp having a bulb socket with a lamp bulb seat that will hold the lamp bulb in axial alignment with the bulb socket.

Furthermore, when the lamp bulb is seated in the bulb socket there is no resiliency between the lamp bulb and the rivet upon which it seats so vibration tends to loosen the bulb 30 in the bulb socket. Therefore, another object of this invention is to provide a hand lamp with a bulb socket having a resilient contact with sufficient friction to prevent the bulb from becoming loosened in the socket 35 and disconnected from the battery circuit.

In hand lamps constructed with a small head, as shown in the applicant's patent above mentioned, it is desirable, and sometimes necessary, to use lamp bulbs having a glass globe of small size. When the bulb socket and reflector are made in a unit as shown, it is frequently difficult to remove and replace the lamp bulb without injuring or soiling the reflector. Therefore, another 45 object of this invention is to provide a hand lamp having a bulb socket from which a bulb may be readily removed without injuring or soiling the reflector.

50 In miniature lamp bulbs, such as used in hand lamps and flashlights, the filament is

frequently not on the axis of the lamp base. Consequently, when such a lamp bulb is used in a hand lamp, the bulb filament is not on the axis of the reflector and, as a result, the projected beam of light is distorted and lessened in intensity. Mr. H. W. Jones, in his patent mentioned above, shows a mechanism for bringing the bulb filament into coincidence with the axis of the reflector. But, in this construction, no provision is made for holding the reflector and lamp socket in axial alignment and, consequently, the reflector must be manually adjusted and aligned with the filament of every lamp bulb that is placed in the lamp socket regardless of whether the filament is in alignment with the lamp base or not. This is a cause of much annoyance to the users who have no inclination to make the finer adjustments and are satisfied with ordinary results. Therefore, another object 55 of this invention is the provision of a hand lamp having a bulb filament and reflector aligning device that normally holds the filament of a concentric lamp in alignment with the reflector axis, but may be manually moved 60 to position the filament of an eccentric lamp 65 at the axis of the reflector.

Other aims and objects of this invention will be apparent from the specification and drawing.

The objects of this invention are attained by the mechanism illustrated in the accompanying drawing which is a longitudinal section of a hand lamp embodying my invention.

80 In the drawing 10 designates a tubular casing of metal or other suitable material containing the usual battery B of dry cells. These cells may be inserted and removed through the bottom end of the casing 10 85 which is closed by a removable cap 11 carrying a conductive battery support 12 forming electrical contact with the bottom of the battery B and also a compartment for spare bulbs.

90 The top or head end 15 of the casing 10 is slightly enlarged and threaded to receive a conversely threaded head fitting 16 having an inwardly projecting bead 17 formed in its wall just above the threaded portion 18. The 95 100

upper end of the head fitting 16 is turned outward thereby forming a flange 19 upon which the flanged outer edge 20 of the reflector R rests. A cover glass G rests upon and closes the outer end of the reflector R with which it is held in axial alignment by the annular upturned edge 21 of the reflector flange 20.

Surrounding the upper portion of the head fitting 16, from which it is spaced, is a clamping ring 22 having a central threaded portion 23, an upper edge 24 turned inward at a slight angle and seated against the under side of the flange 19, and an inturned lower edge 25 that may rest against the outside of that portion of the wall of the head fitting forming the upper side of the bead 17. A threaded bezel 26 is screwed over the threaded portion 23 of the clamping ring 22 and thereby clamps the cover glass G and reflector R to the head fitting 16, and a ring of resilient material C such as sponge rubber is confined in a partially compressed condition between the inner surface of the clamping ring 22 and the other surface of the head fitting 16, thereby normally holding the ring 22, bezel 26, cover glass G; and reflector R, in axial alignment with the lamp bulb L.

Fitting snugly within the threaded portion 15 of the casing 10 is a sleeve 27 of insulating material such as fiber or paper. Carried by the sleeve 27 is a transversely extending diaphragm 28 having a cylindrical upturned edge 29 that fits snugly within the sleeve 27 and an outturned edge forming a flange 30 that rests on the upper end of the sleeve 27. Between the flange 30 of the diaphragm 28 and the inturned bead 17 of the head fitting 16 is an apertured washer 31 of insulating material that insulates the flange 30 from the bead 17. When the head fitting 16 is screwed on the casing 10 the inturned bead 17 clamps the washer 31, flange 30 of the diaphragm 28, and sleeve 27 to the end of the casing 10.

Integral with the diaphragm 28 and depending from the center thereof is a flange or sleeve 32 in which slides a bulb socket 33 having internal threads in the upper end thereof that receive and hold a conversely threaded bulb L so the bottom of the metal bulb base 34 seats upon an annular shoulder 35 extending inwardly from the wall of the socket at the bottom of the threaded portion thereby holding the bulb in alignment with the socket and preventing any tendency for the bulb to cock sidewise out of alignment. Encircling the sleeve 32 and socket 33, and confined between the under side of the diaphragm 28 and the upper side of an annular flange 36 extending outwardly from the lower end of the lamp socket 33, is a partially compressed retractile spring 37 that tends to hold the lamp socket 33 in its lowermost position with the annular flange 38 ex-

tending outwardly from the upper end of the lamp socket in contact with the upper side of the diaphragm 28. Riveted in a recess in the bottom of the lamp socket 33 is an apertured washer 39 of insulating material such as fiber or bakelite, and riveted in the aperture in the center of the washer 39 is a conductor 40 having an enlarged end 41 extending downward and making contact with the positive terminal 42 of the battery B, and a reduced end 43 extending upwardly into the lamp socket 33. Surrounding and supported by the reduced portion 43 of the conductor 40 is a bulb contacting spiral spring 44 that fits loosely around the end 43 and is held thereto by its lower convolution 45 which is contracted so it grips the lower part of the end 43. The upper convolution 46 of the spring 44 is formed so it lies approximately in a plane transverse to the axis of the lamp bulb and so that practically the entire upper convolution 46, or several portions thereof, are in contact with the central terminal of the lamp bulb L. The retarding force of the friction between the central terminal of the bulb L and the upper convolution 46 of the spring 44 is greater than the rotative force of the spring pressure on the bulb L against the threads in the lamp socket 33. Consequently, if the lamp bulb L should become loosened from its seat against the shoulder 35 as a result of intense vibration, it will not become unscrewed from the socket 33 far enough to become disconnected from the contact spring 44 and thereby become inoperative. Instead, it will become unscrewed only a portion of a turn necessary to distort the spring 44 so its resistance equals and counteracts the rotative force of the lamp bulb L.

Mounted upon the outside of the casing 10 is a conventional switch 47 which is connected to the diaphragm 28 by the usual contact strip 48. When the switch 47 is in closed circuit position the path of the electric circuit through the flashlight is from the positive terminal 42 of the battery B to the conductor 40, contact spring 44, lamp bulb L, bulb socket 33, diaphragm 28, contact strip 48, switch 47, casing 10, end cap 11, and battery support 12, to the negative terminal of the battery B.

If the light beam projected from the flashlight when it is in operation is distorted on account of the lamp and reflector not being in focus, they may be adjusted axially by screwing the end cap 11 either on or off the casing 10, to a greater or less extent, thereby moving the battery support 12, battery B, lamp socket 33, and bulb L, in relation to the reflector. Normally, the resilient ring C holds the clamping ring 22, bezel 26, cover glass G, and reflector R, in axial alignment with the head fitting 16, so the reflector R is, consequently, in axial alignment with the bulb L. If the filament of the bulb L is not in

axial alignment with the base 34 and consequently, not in alignment with the axis of the reflector R, the bezel 26 may be partially unscrewed from the clamping ring 22 to release 5 the reflector R and cover glass G, and then the ring 22, bezel 26, cover glass G, and reflector R, may be manually moved transversely to the axis of the reflector and bulb, against the pressure of the resilient ring C, and in a direction indicated by the character of the projected light beam, so the axis of the reflector R and the filament of the bulb L are in coincidence where they may be held by tightening the bezel 26. By a combination of the 15 above mentioned axial and transverse movements the bulb and reflector may be quickly and accurately focalized. As the resilient ring C normally holds the reflector in axial alignment with the bulb, the transverse focalizing adjustment need not be used except in cases where the lamp filament is not in axial 20 alignment with the lamp base.

By removing the head fitting 16 and its associated parts from the casing 10 the lamp bulb L is exposed so it may be removed from the socket 33 and reinserted or replaced without injuring or soiling the reflector in any way.

Various changes in the form, construction, 25 and arrangement of the component parts of the flashlight may be made without departing from the spirit of the invention or sacrificing any of the rights thereunder.

I claim:

25 1. The combination in a flashlight comprising a lamp bulb, and a reflector in operative relation thereto, of means for moving said lamp bulb along the axis of said reflector, a resilient member for holding said reflector in axial alignment with said lamp bulb, and means for moving said reflector out of axial alignment with said bulb against the pressure of said resilient member.

2. The combination in a flashlight comprising a lamp bulb, and a reflector in operative relation thereto, of means for moving said lamp bulb along the axis of said reflector, a resilient member for holding said reflector in axial alignment with said lamp bulb, means for moving said reflector in any direction transverse to its axis against the pressure of said resilient member to adjust said reflector out of axial alignment with said lamp bulb, and means for holding said reflector in any of its adjusted positions.

3. The combination with a flashlight comprising, a casing, a reflector within said casing, a bulb within said casing and in operative relation to said reflector, a battery within 30 said casing adapted for energizing said bulb, a cap closing one end of said casing and adjustable thereon, and rigid means within said cap for supporting said battery within said casing, of means including said battery and said rigid means for moving said bulb along

the axis of said reflector by adjusting said cap on said casing, a resilient member for holding said reflector in axial alignment with said bulb, means for moving said reflector in any direction transverse to its axis against the 70 pressure of said resilient member to adjust said reflector out of axial alignment with said bulb, and means for holding said reflector in any of its adjusted positions.

4. In a flashlight, a reflector having an aperture at its apex, a lamp bulb projecting through said aperture in operative relation to said reflector, a resilient member for holding said reflector in axial alignment with said lamp bulb, and means for moving said reflector against the pressure of said resilient member to position said reflector out of axial alignment with said lamp bulb.

5. In a flashlight, a reflector having an aperture at its apex, a lamp bulb projecting through said aperture in operative relation to said reflector, a resilient member for holding said reflector in axial alignment with said lamp bulb, means for moving said reflector against the pressure of said resilient member to adjust the position of said reflector so it is out of axial alignment with said lamp bulb, and means for retaining said reflector in said adjusted position.

6. In a flashlight, a reflector having an aperture at its apex, a lamp bulb projecting through said aperture in operative relation to said reflector, a resilient rubber ring for holding said reflector in axial alignment with said lamp bulb, means for moving said reflector against the pressure of said resilient rubber ring to adjust the position of said reflector so it is out of axial alignment with said lamp bulb, and means for retaining said reflector in said adjusted position.

7. In a flashlight, a tubular metal casing having an expanded end with a thread thereon, a sleeve of insulating material within said expanded end, a diaphragm in said casing having a flange resting on said sleeve, a lamp socket carried by said diaphragm, a lamp in said lamp socket, an apertured washer of insulating material resting on said flange, a head fitting threaded to said expanded end and clamping said washer, said diaphragm and said sleeve to said casing, an apertured reflector carried by said head fitting in operative relation to said lamp, a battery within said casing, and means for completing the circuit through said battery and lamp at will.

8. In a flashlight, a tubular metal casing, a diaphragm within said casing having a central depending integral sleeve, a lamp socket within said sleeve, an upper flange extending outwardly from the upper end of said lamp socket, a lower flange extending outwardly from the lower end of said lamp socket, a spring confined between the under side of said diaphragm and the upper side of

- said lower flange in a partially compressed condition, a washer of insulating material having an aperture therein riveted in a recess in the lower end of said lamp socket, a conductor riveted in the aperture in said washer, a lamp in said lamp socket, a coiled spring carried by said conductor and contacting with said lamp, a reflector carried by said casing in operative relation to said lamp,
- 5 means for moving said lamp socket in said sleeve to focalize said lamp and said reflector, a battery within said casing, and means for completing the circuit through said battery and said lamp at will.
- 10 15. 9. In a flashlight, a casing having a lamp bulb therein; a head fitting threaded to said casing and having an outturned flange on the upper end thereof; an apertured reflector having a flat rim with an upturned edge resting on said flange so said reflector is in operative relation to said lamp bulb and is movable laterally with respect to said bulb and said head fitting; a cover glass resting on said flat rim within the upturned edge thereof
- 20 and movable therewith; a threaded bezel resting on said cover glass and movable therewith; a clamping ring threaded to said bezel and resting against the under side of said flange and movable with said reflector,
- 25 cover glass, and bezel, to align the axis of said reflector with the filament of said lamp, and adjustable with respect to said bezel to secure said reflector and cover glass in any adjusted position; a rubber ring confined
- 30 between said clamping ring and said head fitting in a partially compressed condition for the purpose of normally holding said reflector in axial alignment with the base of said lamp but permitting said reflector to be moved out of axial alignment at will; a battery within said casing; and means for completing the electric circuit through said battery and said lamp bulb at will.

In testimony whereof, I affix my signature.

LEE J. VOORHEES.
